J. A. PEASE.
CLOTHES DRIER.

No. 36,726.

Patented Oct. 21, 1862.

UNITED STATES PATENT OFFICE.

JULIUS A. PEASE, OF NEW YORK, N. Y.

IMPROVED CLOTHES-DRIER.

Specification forming part of Letters Patent No. 36,726, dated October 21, 1862.

To all whom it may concern:

Be it known: that I, JULIUS A. PEASE, of the city, county, and State of New York, have invented a new and Improved Clothes-Drier; and I do hereby declare the following to be a full, and exact description of the same, reference being had to the accompanying drawings and to the letters of reference marked thereon.

The nature of my invention consists in combining and arranging a number of arms or rails in such a manner as to obtain a great length of drying-surface in a small space, and so arranged as to fall out of the way when not in use.

To enable others skilled in the art to make and use my invention, I will proceed to describe its construction and operation.

I construct my drier of any size and shape. The back B, Figures 1 and 2, is made of a flat piece of wood to which is attached swinging

piece A, by means of hinges c c. The arms D are fastened at one end in slots E in swinging piece A, by means of two pieces of metal, F F, forming a clamp and holding the said arm firmly in their places. When not in use the arms are folded against the back B, and are entirely out of the way. When wanted for use, raise the arms to a horizontal position and fasten by means of hook H and staple I. It will be seen that a large amount of drying-surface is obtained by this arrangement, and in a small space.

What I claim as my invention, and desire to secure by Letters Patent, is—

The combination and arrangement of a clothes-drier, substantially as before described.

JULIUS A. PEASE.
